CLOCK FACE

Robert W. Windebank, Fairfield, and Reinhardt F. Luthmann, Wilton, Conn., assignors to General Time Corporation, Stamford, Conn., a corporation of Delaware

Filed Dec. 12, 1968, Ser. No. 14,950

Term of patent 14 years

Int. Cl. D10—06

U.S. Cl. D42—7

FIG. 1

FIG. 2

FIG. 3

FIGURE 1 is a perspective view of a clock face showing our new design;

FIG. 2 is a front elevational view thereof; and

FIG. 3 is a fragmentary front elevational view of a clock face showing another form of our new design wherein the outermost ring of 60 apertures is comprised of circular perforations.

We claim:

The ornamental design for a clock face, as shown and described.
